EDWARD A. COOMBS, OF PLAINVILLE, MASSACHUSETTS, ASSIGNOR TO WHITING CHAIN COMPANY, A CORPORATION OF MASSACHUSETTS.

BRACELET.

Application filed May 7, 1924. Serial No. 711,579.

This invention relates to bracelets, and more particularly to bracelets of the type commonly used in connection with wrist watches. Such a bracelet usually consists of a strap or band to encircle the wrist, which is secured to the watch by being led through loops attached to the watch case, and a clasp so arranged as to permit the girth of the band to be enlarged whenever the bracelet is to be slipped over the hand. For this latter purpose the band is provided with overlapping portions, the length of which may be adjusted so as to vary the size of the bracelet, and when the clasp is unfastened, the excess length provided by these overlapping portions is drawn through one of the watch loops so that the girth of the bracelet is increased to that extent. The band is usually made of a piece of fabric tape or ribbon and the clasp is formed of two members attached to the band, and which have interengaging portions. The position of the clasp members on the band determines to what extent the portions of the latter will overlap, and consequently the position of the clasp members must be adjusted according to the size of the wrist of the wearer. One of the clasp members is usually attached to the end of the band and the other is so formed that the tape may be threaded through it so that the position of the second member may be varied as desired. Owing to the fact that the latter member must necessarily be movable along the tape and is held in position only by friction, it frequently happens that this clasp member will slide along the tape, especially after the latter has become worn. This causes the strap to be loosened and requires that an adjustment be made. Furthermore, it is difficult to adjust the position of the clasp member so as to give the bracelet the desired size without being either too tight or too loose. The bracelet might be made to fit the wrist snugly by making the tape of elastic material, but the life of such material is quite short, and its use is undesirable for that reason.

The object of the present invention is to provide a bracelet of attractive design which affords numerous advantages over bracelets as heretofore constructed, by reason of its including a member which permits a slight expansion of the band so that when the

movable clasp member has been properly adjusted, the bracelet when closed will encircle the wrist snugly at all times, but will yield whenever the movements of the wrist may so require. This bracelet consists of the usual band, the two clasp members, and a take-up member provided with spring-held parts, which is inserted so as to form a part of the band with portions of the band secured to these parts. The latter may be moved relatively to one another so as to increase the girth of the band slightly, and when the force tending to produce this result is removed the spring-held parts are restored to their normal positions, thus restoring the bracelet to its original sizes. The take-up member is so constructed that all its operative parts are concealed and its exposed portions have an attractive appearance and may be decorated in any suitable manner, as, for instance, by engraving a monogram upon them.

In the accompanying drawings there is illustrated that embodiment of the invention which is now preferred, and in these drawings,

Fig. 1 is a perspective view of such a bracelet attached to the watch,

Fig. 2 is a longitudinal cross-sectional view of the take-up member on the line 2—2 of Fig. 1,

Fig. 3 is a view of the take-up member in longitudinal cross-section, taken in a plane substantially parallel to the plane of the band,

Figs. 4 and 5 are cross-sectional views through the take-up member on the lines 4—4 and 5—5 respectively, of Fig. 3,

Fig. 6 is a view in perspective of a plate forming part of the take-up member, and

Fig. 7 is a view in perspective of a pair of plungers which are used in the take-up member.

Referring now to these drawings, the bracelet is shown in use attached to a watch in Fig. 1. This bracelet consists of a strap or band 1 secured to the watch 2 by means of loops 3 formed integrally with the case of the watch. One end of the band 4 is sewed to a clasp member 5, while another portion of the band is led through a cooperating clasp member 6, having a stud which may be frictionally engaged in an aperture in the member 5. The band, as illustrated

80

105

at 7, is led through spaced slots in the member 6 so that the latter may be moved along the band to any desired position of adjustment. Ordinarily one end of the band, as 5 at 8, is secured to one of the loops 3. This band passes through the clasp member 6, the end is led through the second watch loop, and then on the end of this band is mounted the second clasp member 5. With this arrangement the band has an overlapping portion so that when the clasp members are separated the excess length provided by the overlapping portion may be drawn through the loop 3, thus increasing the girth of the 10 band sufficiently to permit it to be slipped over the hand. For the purpose of illustrating the construction clearly, the band shown in Fig. 1 is of considerably greater girth in proportion to the size of the other parts 15 than is ordinarily the case. With this type of bracelet it will be seen that the clasp member 6 must be moved along the band so that when the clasp is fastened together the band will fit the wrist tightly. It is somewhat difficult to make this adjustment so 20 that the watch may be worn with comfort and, furthermore, the movements of the wrist of the wearer frequently increase the girth of the band so that the bracelet exerts 25 an uncomfortable pressure. This may result in causing the clasp member 6 to be slipped along the band, thus destroying the adjustment and making the bracelet too loose under normal circumstances.

30 In order to overcome this condition and to provide the bracelet with a certain degree of elasticity, such as might ordinarily be secured by making use of an elastic fabric, which, however, as has previously been explained, is altogether undesirable, I insert a take-up member 9 in the band, preferably 35 between the clasp member 6 and the loop 3 to which the end 8 of the band is attached. The band is cut between the clasp member 40 and the end 8, and the ends so provided are secured to spring-held parts of the take-up member. These parts are concealed when the take-up member is in use, and the latter simply has the appearance of a plate which 45 may be decorated by a suitable monogram. This take-up member is preferably formed on a slight curve so as to fit the contour of the wrist.

50 The take-up member 9 comprises a plate 5 having upstanding lateral flanges 11, and disposed between these flanges is an open-sided casing 12, placed with its open side against the inner face of the plate 10. The plate thus forms a side wall for the casing 55 and extends beyond the ends thereof. The ends 13 of the casing are bent at right angles to its main wall 14 and these ends have flanges 15 which bear against the face of the plate 10. The flanges 11 of the plate are 60 cut so as to provide tongues 16 which are

turned inwardly to overlie the flanges 15 and thus hold the casing anchored in position against the plate.

The ends of the casing are formed with pairs of slots 17, shown in Fig. 5, the slots 70 in one end being placed comparatively close together near the middle of the end, while the slots in the other end are placed near the outer edges as shown in Fig. 3. Mounted in the ends of the casing are 75 plungers 18, shown in Fig. 7. Each plunger has a pair of legs 19 which lie side by side, these legs passing through the slots 17 and extending to a considerable distance within the casing. The ends of the legs have heads 80 20 which prevent the removal of the plungers from the casing, and at their outer ends the legs are connected by a loop 21, through which the end of the band 8 is led and held in position by sewing. Within the casing 85 each leg is encircled by a spring 22 which bears at one end against the inner end wall of the casing, and at the other against the head 20. These springs are arranged so as to cause the plungers to be normally re- 90 tracted into the casing. It will be seen that the plungers are alike in construction, save as to the position of the legs, which are placed so that the plungers may move freely relative to each other without interference. 95 The loops 21 which lie beyond the ends of the casing are guided in their movement by the inner wall of the flanges 11 and the plungers may be moved apart against the force of the springs 22. The springs are of 100 light wire so that they offer but little resistance to the outward movement of the plungers, thus permitting the band to yield whenever the movements of the wrist so require. The plate 10 is sufficiently long so 105 that the plungers at their extreme movement do not pass beyond the ends of the plate and the operative parts of the take-up member are concealed from view by means of a flanged plate 23, the flanges of which fit over 110 the flanges 11 on the plate 10. This cover plate has a curvature similar to that of the plate 10, and near the ends of the flanges formed on it are small projections which 115 may engage in suitable recesses 24 formed in the flanges 11. The engagement of the studs with the recesses serves to lock the cover plate in position. The cover plate is about the same length as the plate 10 and with this plate serves to provide a guide-way for the plunger movements as well as concealing those portions of the plungers which lie outside of the casing 12.

120 Whenever a new band is to be made use of in the bracelet a length of this band is secured to one of the loops of the watch by sewing and is then sewed to the loop of one of the plungers, the cover plate of the take-up member being removed for the purpose. The end of another piece of band is 125 130

sewed to the loop of the other plunger, is then led through the clasp member 6, through the other watch loop, and then the end of this portion of the band is secured 5 to the second clasp member. The length of the different parts of the band may be readily determined by placing the bracelet on the hand and putting the parts in their proper adjusted position before the clasp member 5 is finally sewed to the end of the band. The cover plate of the take-up member is then restored and the bracelet is ready for use. It is slipped over the hand in the usual way, the clasp members fastened, and thereafter the band grips the 15 wrist with a yielding pressure so that the bracelet may be worn with great comfort. Owing to this slight elasticity provided by the take-up member, the slide clasp member 20 6 need not be adjusted with great accuracy.

Since all the working parts of the take-up member are concealed from view it may be given an attractive appearance and may be 25 made of any desired metal, as, for instance, the same metal as the watch. Also, since it is not necessary to make the band of elastic material, fabrics which have a much longer life than elastic fabric may be employed, while the bracelet has all the desirable qualities of an elastic band. The take-up member contains no parts which become worn when in use, and may be used 30 for an indefinite period. In a bracelet 35 which includes this take-up member the band encircles the wrist snugly but without uncomfortable pressure, and this regardless of the movements of the wrist of the wearer. Since the bracelet yields slightly whenever 40 required, by reason of the presence of the take-up member, no excessive strain is placed on the fabric when the bracelet is in use, and thus the fabric has an increased life and need not be replaced so frequently.

45 I claim:

1. For use in combination with an ornamental article of the encircling type, a take-

up device comprising a casing, plunger members having portions thereof slideable into said casing and having ends adapted for 50 attachment to the ends of the encircling article, springs within the casing for normally holding the plunger members in retracted position, and a cover member overlying the casing and plunger members adapted 55 to conceal the same even though the plunger members be in their extended position.

2. A take-up device for an encircling member comprising a base plate having opposite sides thereof extending upwardly, another plate fitting within said base plate to form a casing, spring-pressed plunger members each comprising a portion adapted for 60 attachment to the ends of the encircling member, and a portion adapted to extend 65 within said casing, said last-mentioned portion being normally held in retracted position within the casing, a cover piece overlying the whole, sufficient in length to conceal 70 all the parts even though the plunger members be in their extended position.

3. A take-up device for an encircling member comprising a base plate having opposite sides thereof extending upwardly, a second plate fitting within said base plate to 75 form a casing, portions of the upwardly extending sides of the base plate being cut so as to form tongues adapted to hold the second plate in fixed position, plunger members each comprising a portion adapted for 80 attachment to the ends of the encircling member and a portion adapted to extend within said casing, springs associated with said last-mentioned portion for normally maintaining the last-mentioned portion of the 85 plunger members in retracted position within the casing, a cover member overlying the base plate and attachable thereto, said cover plate being of sufficient length to completely conceal both the base plate and the 90 plunger members even though the plunger members be in their extended position.

In testimony whereof I affix my signature.

EDWARD A. COOMBS.
